CLAIM

The ornamental design for a biopsy sample container, as shown and described.

DESCRIPTION

FIG. 1 is a perspective view of a biopsy sample container showing the new design;

FIG. 2 is a top view plan view thereof;

FIG. 3 is a bottom plan view thereof;

FIG. 4 is a left side elevational view thereof;

FIG. 5 is a right side elevation view thereof;

FIG. 6 is a front elevational view thereof;

FIG. 7 is a rear elevational view thereof; and,

FIG. 8 is a perspective view of the biopsy sample container in a closed configuration.

The broken lines in the drawings depict portions of the biopsy sample container that form no part of the claimed design.
